UNITED STATES PATENT OFFICE.

HENRY BERRY, OF HUNTINGTON, ASSIGNOR TO THE DERBY SILVER COMPANY, OF BIRMINGHAM, CONNECTICUT.

DESIGN FOR A CARD-RECEIVER.

SPECIFICATION forming part of Design No. 17,073, dated January 25, 1887.

Application filed December 8, 1886. Serial No. 221,021. Term of patent 3½ years.

To all whom it may concern:

Be it known that I, HENRY BERRY, a citizen of the United States, residing at Huntington, in the county of Fairfield and State of Connecticut, have invented and produced a new and original Design for Card-Receivevers; and I do declare the following to be a full, clear, and exact description of the same, reference being had to the accompanying drawings, forming a part thereof.

Figure 1 of the drawings is a side view of my newly-designed card-receiver, and Fig. 2 is a plan view thereof.

B is a plate mounted on a stand or base. This plate is of rectangular contour, having its three visible corners bent down, as shown, and its entire rim ornamented with the representation of a rope.

A is the handle, arranged above one of the corners of the plate. From opposite sides of

this handle are represented, in a spread manner, the wings of an eagle.

Across the middle of the face of the plate is represented a bar of music, which is partly enclosed by a spray of flowers.

25

I claim—

The design for a card-receiver herein shown and described, the same consisting of a plate of rectangular contour, having its edge representing a rope and its three visible corners turned down, a handle on one corner, and a spread wing on each side of the handle, substantially as specified.

30 In testimony whereof I affix my signature in presence of two witnesses.

HENRY BERRY.
